UNITED STATES PATENT OFFICE.

CLAUDE M. DIBBLE, OF JOLIET, ILLINOIS, ASSIGNOR TO MOORE BROTHERS COMPANY, OF JOLIET, ILLINOIS, A CORPORATION OF ILLINOIS.

STOVE CONSTRUCTION.

Application filed August 7, 1926. Serial No. 127,793.

This invention relates in general to stoves and more particularly to the construction of the oven and high shelf of cabinet gas ranges and the like.

5 An important object of the invention is to provide a cabinet gas range or the like, the oven parts or plates of which are so arranged and assembled that there will be no projections from the wall plates, such as screws or 10 the like, after the stove is assembled. In devices of this character provided heretofore the wall plates of the oven have been fastened together and to the frame and rear wall plate by screws or like devices that are 15 unsightly and difficult to keep clean and for this reason unsanitary. Further, when a stove is assembled by means of screws a stove is frequently damaged during assembly to the extent that new parts must be supplied 20 since the stoves of this type now in general use are coated with a hard and brittle enamel that cracks easily when strained. This may occur at the time of assembly by drawing the screws too tight and may occur at any 25 time thereafter, because of the unequal expansion of the oven plates and the screw body. In constructing and assembling a stove in accordance with my invention this cannot occur either at the time of assembly or there- 30 after since the plates are interlockingly engaged and secured in place by means of screws in concealed positions and bolts that need not be drawn up excessively tight.

Another important object in the invention 35 is to provide a means adapted to be positioned between overlapping parts of the oven walls to hold the parts in predetermined relative position and to prevent the passage of air, such as heated air from the oven, or cold 40 air from the outside.

Another important object in the invention is to provide such a device in which the high shelf is similarly secured in position or is supported by an oven wall plate or the like 45 and held in assembled position by the oven top plate so that no screws or like devices will be required for attaching or supporting the end of the high shelf on the oven.

Another important object in the invention 50 is to provide such a device that may be assembled without the use of a large number of screws, bolts, or the like and that for this reason may be manufactured at a low cost and more rapidly assembled than similar 55 devices.

Numerous other objects and advantages of the invention will be apparent as it is better understood from the following description, which, taken in connection with the accompanying drawings, discloses a preferred embodiment thereof.

Referring to the drawings:

Figure 1 is a front elevational view of a cabinet gas range embodying my invention;

Fig. 2 is a top plan view of the device 65 shown in Fig. 1;

Fig. 3 is a section taken substantially on line 3—3 in Fig. 2; and

Figs. 4 and 5 are sections taken substantially on lines 4—4 and 5—5 respectively in 70 Fig. 3.

To illustrate my invention I have shown a stove of the type commonly known as a cabinet gas range having a frame 11 suitably supported on legs 12 and having an oven 75 part 13 and an open burner part 14 provided with suitable burners and fuel connections. The frame 11, legs 12 and oven part 13 may be of any suitable type, the oven 13 having side wall plates 15, rear wall plates 16, a door 80 frame 17 and a top plate 18. The open burner part 14 may also be of any suitable type and form and provided with any suitable number of burners.

The side wall plates 15, usually two in 85 number one for each side, are preferably offset toward the inside of the oven (Figs. 4 and 5) to provide a shoulder 21. It will be understood, however, that other wall plates may be provided where a double wall is 90 required for the oven. The rear wall plate 16 is preferably a flat plate that may be apertured at a plurality of points to receive screws or bolts 22. The door frame 17 may be of any suitable form and provided with 95

any type of door 23 and a laterally extending flange 24. One or more suitable lugs 25 may be cast on or suitably attached to the inside of the door frame 17 and apertured to receive a screw 26. The screw may have 100 threaded engagement in the aperture or in a suitable threaded nut or the like. The top plate 18 is preferably provided with depending flanges 27 extending along its side edges that are preferably turned back along their 105 edges 28 to provide a rounded or square edge. The rear edge of the cover plate 18 is also provided with a depending flange 29 that may be similarly curled at its lower edge upon occasion and in the present in- 110

stance is shown flat. The front edge of the top plate is formed to provide a laterally extending portion 31 and preferably bent downwardly and laterally as shown (Fig. 3) 5 to engage beneath the laterally extending flange 24 of the door frame 17 a sufficient distance to be engaged by the screw 26 in the lugs 25. The wall plates 15 may be similarly flanged and secured to the door frame 10 upon occasion. The top edge of the side wall plate 15 adjacent the open burner part and above which is or may be mounted a high shelf 32 is cut away as at 33 to provide a slot or recess. The high shelf 32 may be 15 suitably attached to a frame part 34 in any suitable manner and similarly to the rear wall plate 16. The edge of the high shelf adjacent the wall plate 15 is formed to provide a depending flange 35. A lip or tongue 36 which may be suitably attached to or formed as a part of the depending flange 35 is preferably offset as at 37 to extend through the recess 33 to support the high shelf on a shoulder 38 of the recess 33 and engage the 25 inner surface of the wall 15. A strip 41 that is preferably substantially V shaped in cross section is preferably positioned over the top edge of the plate 15 and arranged to engage within the curled edge 21 of the top plate 18 to provide a means of holding the edge of the top plate 18 and the plate 15 in a predetermined relative position and for preventing the free passage of air between the wall plate and top plate. 30

The wall plates 15 the back plate 16 and door frame 17 may be assembled in any suitable manner and when so assembled the high shelf 32 is assembled to the frame part 34 and rear wall plate 16 with the tongue 36 seated in the recess 33. Where one or more strips 41 are desired these are then assembled to the top plate and it will be noted (Fig. 3) that these may be slid into the position shown from the front and that where 45 a more perfect seal is required, they may be filled with a material such as fire clay before or after assembling the top plate 18. The top plate 18 is then positioned over the wall plates 15, the extended portion 31 thereof shoved under the laterally extending flange 24 of the frame 17 and the plate 18 may then be pressed down into position for locking the tongue 36 of the high shelf in assembled position and may be locked in position by one or more of the bolts 22 extending through the rear wall plate 16 and depending flange 29 of the top plate 28. 50

It is thought that the invention and many of its attendant advantages will be understood from the foregoing description, and it will be apparent that various changes may be made in the form, construction and arrangement of the parts without departing from the spirit and scope of the invention or 60 sacrificing all of its material advantages, the

form hereinbefore described being merely a preferred embodiment thereof.

I claim:

1. In a stove structure, the combination of a door frame, a wall plate arranged to underlie a portion of said frame, and means on the frame for forcing said wall portion into a holding contact with the overlying part of said frame. 70

2. In a stove structure, the combination of a door frame, a wall plate arranged to underlie a portion of said frame, and means on the frame for forcing said wall portion into a holding contact with the overlying part of said frame, said means comprising, an adjustable member adapted to be locked in adjusted position. 75

3. In a stove structure, the combination of a door frame having a laterally extending edge flange, a wall plate arranged to underlie said edge flange, and adjustable means mounted in the door frame and arranged to force the wall plate into contact with the laterally extending flange of said frame. 80

4. In a stove structure, the combination of a door frame having a laterally extending flange, side wall plates secured to said door frame, a rear wall plate secured to said side wall plates, and a cover plate, said cover plate being formed for support by the side wall plates, for attachment to the rear wall plate, and provided with a laterally extending portion adapted to extend beneath the laterally extending flange of the door frame. 90

5. In a stove structure, the combination of a door frame, a rear wall plate, side wall plates, and a top plate, said top plate having depending flanges along its opposite sides and said side wall plates being offset adjacent their top edges to provide a bearing for 105 the depending flanges of said top plate. 100

6. In a stove structure, the combination of a door frame, a rear wall plate, side wall plates, a top plate, said top plate having depending flanges along its opposite sides and said side wall plates being offset adjacent their top edges to provide a bearing for the depending flanges of said top plate, and sealing means arranged to co-operate with the offset portion of the side wall plates, and the depending flanges of the top plate for holding said parts in predetermined relative position. 110

7. In a stove structure, the combination of means providing vertical oven walls, a top plate arranged for attachment to said oven walls and having a depending flange adapted to overlap at least one of the walls, and means having interlocking engagement with the depending flange of the top plate and a side wall for holding said parts in predetermined position. 120

8. In a stove structure, the combination of means providing vertical oven walls, a top plate arranged for attachment to said oven 130

walls and having a depending flange adapted to overlap at least one of the walls, and means having interlocking engagement with the depending flange of the top plate and a side 5 wall for holding said parts in predetermined position, said means being adapted to provide a seal for preventing the passage of air.

9. In a stove structure, the combination of an oven part having side wall plates, a rear 10 wall plate, a door frame, and a detachable cover plate, and an open burner part having a high shelf thereabove, said high shelf being supported at one end by a stove frame 15 part and at its other end by an oven wall plate, and being locked in assembled position by the oven cover plate.

10. In a stove structure, the combination of an oven wall plate having a notch therein, a high shelf positioned adjacent said wall 20 plate and having a lip arranged to engage in the notch of said wall plate for supporting the high shelf, and an oven cover plate formed to lock the lip of the high shelf in the notch in said wall plate upon assembly.

25. 11. In a stove structure, the combination of an oven side wall plate having a portion thereof cut away adjacent its upper edge, a high shelf located at one side of the side wall plate and extending therefrom having an extended portion formed to extend through the cut away portion of the side wall plate and to engage the surface of the wall plate opposite the high shelf, and an 30 oven cover plate formed to lock the high shelf in the cut away portion of the side wall plate upon assembly.

oven cover plate formed to lock the high shelf and side wall plate in predetermined 35 relation.

12. In a stove structure, the combination of an oven side wall plate having a portion thereof cut away adjacent its upper edge, a high shelf located at one side of the side wall 40 plate and extending therefrom having an extended portion formed to extend through the cut away portion of the side wall plate and to engage the surface of the wall plate opposite the high shelf, and an oven top 45 plate having a depending flange adapted to be positioned between the oven side plate and the high shelf, and to lock the lip of the high shelf in the cut away portion of the oven side wall plate. 50

13. In a stove structure, the combination of a front frame having an inwardly extending flange, a wall plate arranged against the inner side of said flange, a lug rearwardly of the overlying portion of said wall plate, 55 and means bearing on the lug and on the overlying portion of said wall plate for forcing the same into engagement with said flange.

14. In combination with a stove structure 60 having overlapping wall portions, a sealing strip arranged to hold the overlapping portions in predetermined relative position and to prevent the passage of air between said portions.

CLAUDE M. DIBBLE.
